UNITED STATES PATENT OFFICE.

ALBERT E. HUTT, OF ARDMORE, PENNSYLVANIA.

SEMI-INCLOSED COLLAPSIBLE UPPER-DECK ROOF.

Application filed April 15, 1925. Serial No. 23,209.

My invention relates generally to a semi-inclosed collapsible, upper deck roof for double deck passenger carrying vehicles or buses, wherein the roof sections when in use extend inwardly from the outer upper deck walls over the rows of transversely arranged upper deck seats having a center aisle between them, the height of the roof, when in use, being greater than the height of the average seated passenger and less than the height of the average standing passenger, so that as the latter walks to and fro in the central aisle, the roof section, when in use, will be about breast high and the standing passenger can readily grasp the same to protect himself against the lurching of the vehicle.

By my invention a single attendant can adjust the semi-inclosed convertible top from open to closed position or vice versa, in a very short period of time and when it is desired to use the vehicle with a completely open top, the convertible roof sections are expeditiously and effectively collapsed or stowed out of sight and out of the way of the upper deck seat occupants.

To the above ends, my invention consists of a novel construction of a collapsible, semi-inclosed upper deck roof having bows and carlines of a novel construction.

It further consists of a novel construction of a roof of the character above described having foldable bows and foldable carlines of novel construction, in conjunction with folding stanchions which latter may be employed if desired.

It further consists of a novel construction of an upper deck roof, which when in unfolded position is normally above the heads of the average seated passenger, and below the heads of the average standing passenger, said roof being provided with a novel construction of folding bows, folding carlines and folding stanchions.

It further consists of a novel construction of a foldable or collapsible upper deck roof having foldable carlines provided with longitudinally extending rods, whose ends are guided in inclined guide slots at the vehicle ends so that when said upper deck roof is collapsed, all the elements thereof are guided and moved accurately and expeditiously into their folded positions.

It further consists of novel means for applying the broad principles of my invention, not only to a semi-inclosed upper deck

roof but also to an upper deck roof which is completely closed when the roof sections are unfolded, said upper deck roof in this latter construction having its inner juxtaposed edge portions meeting at an obtuse angle so that the average standing passenger can readily move to and fro in the center aisle between the oppositely located seats.

My invention further consists of other novel features of construction and advantage, as will be hereinafter fully set forth and pointed out in the claims appended hereto.

For the purpose of illustrating my invention I have shown in the accompanying drawings forms thereof which are at present preferred by me, since they have been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a vertical sectional view of a novel construction of a semi-inclosed, collapsible roof for the upper deck of a double deck passenger carrying vehicle or bus, embodying my invention, the roof sections being shown in unfolded position, and certain parts being shown in elevation.

Figure 2 represents a view similar to Figure 1, but showing the roof sections in folded or collapsed condition.

Figure 3 represents on an enlarged scale a vertical sectional view, partly in elevation, of the right hand portion of Figure 1.

Figure 4 represents on an enlarged scale, a vertical sectional view, partly in elevation, of the right hand portion of Figure 2.

Figure 5 represents on an enlarged scale, a side elevation of the right hand carline seen in Figures 1 and 3, the roof proper being shown in section and the bows omitted.

Figure 6 represents on an enlarged scale a sectional view partly in elevation of the elements seen in Figure 5, in folded or collapsed condition.

Figure 7 represents a section on line 7—7, Figure 4, of my novel construction of foldable or collapsible bows, the window posts being shown in horizontal section, on said line 7—7.

Figure 8 represents a front elevation,

partly in section, of my invention as employed for a completely inclosed upper deck roof, the car seats and the bows being omitted for clearness of illustration.

5 Figure 9 represents on a reduced scale a plan view of the open roof construction seen in Figure 2.

10 Figure 10 represents on a reduced scale a plan view of the completely closed roof construction seen in Figure 8.

Figure 11 represents on a reduced scale a plan view of the semi-inclosed roof seen in Figure 1.

15 Figure 12 represents a plan view of the construction seen in Figure 1, but showing a plurality of the collapsible roof sections, as being employed on each side of the vehicle.

20 Figure 13 represents a plan view of the construction seen in Figure 8, but showing the appearance of the roof when a plurality of the side roof sections are employed.

25 Figure 14 represents on an enlarged scale, a section of the ends of the vehicle, showing guide grooves therein.

Figure 15 represents on an enlarged scale, a vertical sectional view of an upper outer deck wall, showing the manner of guiding the carlines when the roof is collapsed.

30 Figure 16 represents a sectional view of an upper deck wall with the carline in its horizontal position.

Similar numerals of reference indicate corresponding parts.

35 Referring to the drawings:—

As one object of my invention is to provide a longitudinally extending semi-inclosed upper deck one man top, which can be instantly folded or collapsed or unfolded, 40 by a single attendant, which when in unfolded position will afford ample protection for the upper deck seat occupants from the sun or elements and at the same time give the proper ventilation, which is so desirable, I have shown herein a preferred form of construction which is capable of attaining my object, but it is to be understood that slight changes in the manner of collocating and assembling the various elements of my invention may be made without departing from the spirit thereof.

45 In the present construction, I have shown the upper deck 1 of the double deck passenger carrying vehicle or bus, as provided 50 on each side of the center aisle 2 with transverse rows of seats 3 having the backs 4. 5 designates the inner seat supports and 6 the outer seat supports which are located within, and in proximity to the upper deck 60 walls 7. 8 designates the upright window posts, which are spaced at approximately the usual distance apart and provided with the vertical grooves 9 for the reception of the window sashes as will be best understood 65 from Figure 7. The window posts 8 are

each provided with a pair of lugs 10 in which are pivotally mounted the lower ends of the bows 11, the latter consisting of the lower member 12 and the upper member 13 which are pivoted together at the point 70 14. The lower bow member 12 is pivotally mounted on the lugs 10 at the point 15, while the upper bow member 13 is pivotally mounted at the point 16 to the lug or ear 17, which depends from the longer inner carline member 18 of the carline 19. The carline 19 is composed of the longer inner carline member 18 and the shorter outer carline member 20, said carline members being hinged or pivoted together at the point 21. 80 The outer, shorter carline member 20 near its end has a transverse pin 48, best seen in Figs. 7, 15 and 16, which projects from each side thereof and is arranged for vertical movement through oppositely disposed, parallel grooves 49 in a window post 8, the upper end of each groove being arranged upon a curve directed toward the vehicle aisle. The upper terminal of each groove is designated 50 and serves as a stop to limit the 85 movement of pin 48, best seen in Fig. 16. The lower end of each groove 48 is provided with an entrance opening 51 for the pin 48 by means of which the parts may be assembled. Each outer, shorter carline member 20 is notched as at 52 adjacent pin 48, so that when parts 20—18 are shifted to horizontal position, see Fig. 16, the notched part 52 cooperates with fixed pin 22 of the 90 upper extension 23 of the window posts 8. 100 24 designates the end walls of the bus in which are located the guide grooves 25, which extend downwardly and inwardly, as will be understood from Figs. 1 and 2, in which grooves ride the ends of the longitudinally extending rods 26, as will be understood from Fig. 14, each of said rods 26 passing through the inner end of the inner longer carline member 18 which is provided with the curved curtain supporting 105 wall 27, upon which the inner end of the curtain 28 is secured, the outer end of said curtain being fixedly secured at the points 29. 30 and 31 designate thin sheet metal plates or bars whose approximate positions are 110 best seen in Fig. 5. The plate 31 extends over the hinge or pivotal point 21 while the plate 30 is located inwardly thereof. 32 designates a folding stanchion, which has its lower end pivoted at 33 to the upper 115 portion of the inner seat support 5, said folding stanchion being of U shape in cross section so that when it is folded into horizontal position, as seen in Figs. 2 and 4, it can rest upon the upper edge of a seat back 120 4. This folding stanchion 32 can of course be omitted if desired.

125 It will be understood from the foregoing, that when the right and left hand roof sections which I have indicated as 34 in Figs. 130

1 and 11 appear unfolded as seen in said figures, a rigid and durable semi-inclosed roof construction is provided, which extends over each of the rows of transverse seats 5 leaving the space above the center aisle 2 open, said roof sections being slightly above the head of the average seated passenger and below the head or about breast high of the average standing passenger. By this construction of roof, a semi-inclosed upper deck 10 is provided, which can readily pass under viaducts, trolley wires and the like, and it will at the same time, shelter the upper deck seated passengers from the sun and the elements. When the roof sections 34 seen in 15 Figs. 1 and 11 are collapsed, it will be evident that the upper deck roof will then appear as seen in Figures 2 and 9, the entire space between the upper deck walls being 20 open as indicated at 35 seen in Figures 2 and 9. In the construction seen in Fig. 8, I have shown the carlines 36 on each side as being composed of an inner longer member 37, and the outer shorter member 38, 25 said members being hinged together or pivotally connected at 39. The outer shorter carline member 38 is hinged at the point 40 to the upper end 23 of the upper deck wall 7 as already described. The inner ends of 30 the longer carline members 37 seen in Fig. 8 are however not bent downwardly as seen in Figs. 1, 3 and 5, but are rectilinear, so that they meet at the apex 41 which is in alignment with the longitudinal, central me- 35 dian line of the vehicle, as seen in Figs. 8 and 10, at which point they can be held in assembled position by screws, bolts or other suitable fastening devices 42, as will be understood from Fig. 8. In the construction 40 seen in Figs. 8 and 10, it will be apparent that the two roof sections 43, when in unfolded position as seen in said figures constitute a completely inclosed upper deck top, which at will can be made completely to inclose upper deck, so that the upper seat occ- 45 cupants will be entirely protected from the sun and the elements, said roof sections 43 being capable of being readily collapsed or folded as will be understood from the left 50 hand portion of Fig. 8. In the construction seen in Fig. 12 I have shown a roof similar to the roof seen in Figs. 1 and 11 but made in two sections on each side thereof, as indicated at 44. In the construction seen in 55 Figure 13 I have shown the roof seen in Figs. 8 and 10, as being made in two sections on each side, said sections being indicated as 45. When the folding stanchions 32 are employed and the roof sections are 60 positioned as seen in Figs. 1 and 3, the upper ends of said stanchions are fastened to the lower juxtaposed ends of the inner carline members 18 by means of any suitable fastening device, as indicated at 46 in said 65 figures. The inner surfaces of the top at the upper outer corners at about the point 70 designated as 23 are adapted for the reception of advertising matter, while the opposite surfaces of the top at about the points indicated at 27 are adapted for inverted advertising matter, so that when the top is collapsed as seen in Figs. 2, 4 and 6, the latter advertising matter appears in a readable 75 position, whereby my invention can readily display advertising matter, irrespective of whether the top is in foldable or unfolded position. The bows when in folded position are locked by a spring catch 47, as seen in Figs. 2, 3 and 4. The operation of folding and unfolding the top is as follows and 80 since both sides function alike, a description of one will suffice for both. In inclement or hot weather the top appears as seen in Figs. 1, 3, 5 and 11. The top curve 28 is held 85 taut by the bows 11, and the carlines 19 and the folding stanchions 32, when employed give additional strength and rigidity to the roof structure. The rods 26, whose ends interlock with the grooves 25, (see Fig. 14) 90 also strengthen the roof structure fore and aft, as is evident.

To collapse the roof, the operator disconnects the fastenings 46. The bows 11 and the carlines 19 are then folded with the position seen in dotted lines Fig. 3, during 95 which movement the notched part 52 of member 20 is caused to disengage from fixed pin 22 so that pin 48 may be free to descend through the grooves 49, which 100 grooves serve to guide the pin 48 in a manner to permit proper folding or collapsing of roof elements. A further outward pressure on the rod 26 causes the roof elements to move from the position seen in Figs. 1 and 3 to the position seen in Figs. 2, 4 and 105 6, the cover 28 being folded neatly upon itself, by virtue of the spring strips 30 and 31, as will be understood from the enlarged view in Fig. 6, and the spring 47 snapping over the contiguous upper end of the bow 110 member 12, as seen in Fig. 4 locks the parts in folded position. During the folding operation, the ends of the rod 26 ride upwardly and outwardly in the grooves 25, and when the top is folded, the ends of said rod are 115 in the upper outer portion of said guide grooves as seen in Fig. 4.

As the bows 11, are in line with the window posts 8, it will be apparent that they 120 are out of the path of the heads of the upper seat occupants.

Having thus described my invention, what I claim as new and desire to secure by Letters Patent, is:—

1. In a device of the character stated, an 125 upper deck, a central aisle therefor, an upper deck collapsible roof structure thereon, transversely foldable jointed carlines therefor extending transversely of said upper deck to said aisle, and having their outer 130

ends pivotally supported above said upper deck and foldable bows having their lower ends pivotally mounted above said upper deck and their upper ends pivotally connected to the inner sections of said carlines.

2. In a device of the character stated, an upper deck collapsible roof structure thereon, transversely foldable carlines therefor extending transversely of said upper deck, 10 end walls for said deck having guide grooves therein, a rod extending longitudinally of said upper deck and carried by said carlines and guided in said grooves, and foldable bows for said carlines.

15 3. In a device of the character stated, an upper deck, a central aisle therefor, an upper deck collapsible roof structure, higher than the head of the average seated passenger and lower than the head of the average 20 standing passenger, transversely foldable jointed carlines therefor, having their outer ends pivotally mounted above said deck, and foldable bows having their lower ends pivotally mounted above said upper deck 25 and their upper ends pivotally attached to the inner sections of said carlines.

4. In a device of the character stated, an upper deck, an upper deck collapsible roof structure, higher than the head of the average seated passenger and lower than the head of the average 30 standing passenger, transversely foldable carlines therefor, having their outer ends pivotally mounted above said deck, and foldable bows having their 35 lower ends pivotally mounted above said upper deck and their upper ends pivotally attached to said carlines, end walls for said deck, having guide grooves therein, and a rod carried by said carlines and guided in 40 said grooves.

45 5. In a device of the character stated, an upper deck, end walls therefor having guide grooves, upright window posts having lugs thereon, transversely foldable carlines, hinged at their outer ends above said upper deck, foldable bows attached to said lugs and carlines, and a longitudinally extending rod carried on the inner ends of said carlines and having its ends mounted in said 50 guide grooves.

55 6. In a device of the character stated, an upper deck, end walls therefor having guide grooves, upright window posts having lugs thereon, transversely foldable carlines, hinged at their outer ends above said upper deck, foldable bows attached to said lugs and carlines, and a longitudinally extending rod carried on the inner ends of said carlines and having its ends mounted in 60 said guide grooves, and a cover carried by said carlines and adapted to be folded in unison therewith.

65 7. In a device of the character stated, an upper deck having a central aisle and oppositely arranged rows of seats, upper deck

outer walls, a collapsible roof extending laterally inwardly over said seats and terminating at said central aisle, transversely foldable carlines having their outer ends pivotally secured to said upper deck outer 70 walls, foldable bows pivoted at their upper ends to said carlines and at their lower ends to lugs projecting inwardly from said upper deck outer walls, a longitudinally extending rod carried by the inner ends of 75 said carlines, and end walls for said deck having guide grooves therein for the ends of said rod.

8. In a device of the character stated, an upper deck, upright window posts each having spaced, oppositely disposed grooves extending from adjacent said deck upwardly, pairs of transversely foldable carlines, each of which is provided with a transversely disposed pin for tracking in said grooves, 80 end walls for said deck having guide grooves therein, and rods carried by said carlines and guided in said grooves.

9. In a device of the character stated, an upper deck, upright window posts each having spaced, oppositely disposed grooves extending from adjacent said deck upwardly, pairs of transversely foldable carlines, the outer of each of which is provided with a transversely disposed pin for tracking in 90 said grooves, and a longitudinally extending rod supported by the upper portions of said posts, the outer of each of said carlines being notched to cooperatively engage with said rod in extended position of said carlines.

10. In a device of the character stated, an upper deck, upright window posts each having spaced oppositely disposed grooves extending from adjacent said deck upwardly, 105 pairs of foldable carlines, the outer of each of which is provided with a transversely disposed pin for tracking in said grooves, the upper terminals of said grooves serving as stops for said pins to limit lateral shifting 110 of said carlines, and the lower portions of said grooves being cut away to provide pin entrance portions for assembling purposes.

11. In a double deck vehicle an upper deck, outer upper deck walls a foldable roof structure above said upper deck said roof structure folding transversely in a plurality of parts toward said outer upper deck walls, end walls for said upper deck having guide grooves therein, and a rod carried by said 115 roof structure and having its ends guided in said grooves.

12. In a double deck vehicle, an upper deck, outer upper deck walls, seats upon said upper deck placed transversely on either side of a central aisle running longitudinally of the vehicle foldable roof structures over said seats terminating at said aisle higher than the average seated passenger but lower than the average standing 125 130

passenger, said roof structure folding transversely towards and against said outer upper deck walls, end walls for said upper deck having guide grooves therein, and a rod carried by said roof structure and having its ends guided in said grooves.

13. In a device of the character stated, a double deck vehicle, an upper deck, outer upper deck walls substantially surrounding said upper deck, an upper deck collapsible roof structure, transversely foldable carlines therefor, having their outer ends pivotally and slidably mounted on said upper deck walls, foldable bows having their lower ends pivotally mounted on said outer deck walls and their ends on said foldable car-

lines, flexible and foldable roof material and means for causing said roof material to fold evenly on itself when said roof is collapsed.

14. In a double deck vehicle, an upper deck, outer upper side walls, a foldable roof structure above said upper deck, and comprising jointed carlines, jointed bows having their upper ends pivoted to said carlines, and their lower ends pivoted to the side walls, longitudinally extending rods carried by said carlines, end walls for said upper deck, and inclined grooves on said end walls, the ends of said rods being received and guided in said end grooves.

ALBERT E. HUTT.
